UNITED STATES PATENT OFFICE.

THOMAS HANVEY, OF ROCHESTER, NEW YORK.

APPARATUS FOR GRINDING WOOD PULP.

SPECIFICATION forming part of Letters Patent No. 242,308, dated May 31, 1881.

Application filed March 17, 1880. (No model.)

To all whom it may concern:

Be it known that I, THOMAS HANVEY, of Rochester, Monroe county, New York, have invented a certain new and useful Improvement in Apparatus for Grinding Wood Pulp; and I do hereby declare that the following is a full, clear, and exact description of the same, reference being had to the accompanying drawings, in which—

10 Figure 1 is a vertical cross-section of the apparatus. Fig. 2 is a similar section at right angles to Fig. 1.

My improvement relates to apparatus for grinding pulp direct from the log.

15 The invention consists in a certain arrangement of parts for feeding the log down to the surface of the grinding-stone and producing pressure on the same, as hereinafter more fully described.

20 In the drawings, A represents the log or bolt of wood from which the pulp is to be ground, and B represents the stone which does the grinding. The log is held at the ends by dogs *a a*, which are driven into it centrally.

25 The dogs are provided with journals *b b*, and at the outer ends of the journals are pulleys *c c*, one at each end of the log. The log thus prepared is capable of rotary motion when mounted in suitable bearings, and when power 30 is applied by bands running on the pulleys *c c*, or by other means. The log A and stone B are both in a frame, C, so that rotary motion may be given to them in opposite directions, as indicated by the arrows in Fig. 1. The journals

35 of the stone rest in stationary bearings, but those of the log rest in vertical slots *d d*, on opposite sides of the frame, which extend so low toward the stone that when the jour-

nals strike in their bottoms the log will be so nearly ground up that only a small core will 40 be left.

D is a hand-lever, which rests over the top of the circular log; and E is a pivoted link forming a fulcrum, to which the lever is attached by means of a hook, as shown in Fig. 1. 45

The stone may be stationary instead of revolving, if desired, and may be made flat instead of cylindrical.

By the use of the slots *d d* and the journals *b b* resting therein, the log will fall centrally 50 over the stone as fast as the surface is ground away. By the use of the lever D the log can be held down to its work with any degree of force desired, which will vary with the kind and condition of the wood which is being acted 55 on. The pressure on this lever also prevents wabbling and jumping of the log. In case of undue speed the lever may also be used as a brake.

Having thus described my invention, what 60 I claim as new, and desire to secure by Letters Patent, is—

In a pulp-machine, the combination, with the grinding-stone B, of the dogs *a a*, set into the ends of the log, the slots *d d* in the frame, 65 in which the journals *b b* of the dogs rest, and the hand-lever D, resting on top of the log and forcing the same down to the stone, as shown and described, and for the purpose specified.

In witness whereof I have hereunto signed 70 my name in the presence of two subscribing witnesses.

THOS. HANVEY.

Witnesses:

R. F. OSGOOD,
CHAUNCEY PERRY.
